UNITED STATES PATENT OFFICE

VALLEJO GANTNER, OF SAN FRANCISCO, CALIFORNIA, ASSIGNOR TO GANTNER & MATTERN COMPANY, OF SAN FRANCISCO, CALIFORNIA, A CORPORATION OF CALIFORNIA

DESIGN FOR A SWEATER

Application filed October 29, 1932. Serial No. 45,635. Term of patent 7 years.

To all whom it may concern:

Be it known that I, VALLEJO GANTNER, a citizen of the United States, residing in the city and county of San Francisco, State of California, have invented a new, original, and ornamental Design for Sweaters, of which the following is a specification.

Referring to the accompanying drawing: Figure 1 is a front view of a sweater showing my new design.

The sweater herein shown is a unitary article.

I claim:

The ornamental design for a sweater substantially as shown and described.

In testimony whereof I have signed my name to this specification.

VALLEJO GANTNER.
